TOBACCO PIPE

Chester C. Doty, Dunkirk, N. Y.

Application April 11, 1949, Serial No. 86,687

1 Claim. (Cl. 131—224)

1 This invention relates to tobacco pipes and the primary object of the invention is to provide a pipe the bowl of which is constructed so that the heat created by the burning of the tobacco during the process of smoking is dissipated readily to keep the pipe cool and provide a cool, dry and mild smoke.

Another object of the invention is to provide a tobacco pipe of the character indicated above the bowl of which is open at its top and bottom ends and is equipped with a cup-shaped tobacco supporting member insertable into the bowl and retained therein by friction between the upper edge portion of the cup-shaped member and the inner surface of the bore of the bowl.

A further object of the invention is to provide a tobacco pipe of the character indicated above, the cup-shaped member of which is arranged in the bowl at such a level that the bottom of said member is located above the lower edge surface of the bowl permitting the pipe to rest in upright position on a table or the like, without the cup-shaped member having contact with the surface of the table.

An additional object of the invention is to provide a tobacco pipe of the character indicated, on the lower edge of the bowl and on the bit of which a plurality of downwardly projecting ribs are formed adapted to cooperate with each other in supporting the pipe in upright position on a table, desk or the like so that the bottom edge surface of the bowl is prevented from contacting the surface of the table, desk or the like to enable cool air to enter into the lower portion of the bowl and contact the cup-shaped member to provide drying, cooling and aeration. The ribs provide a three way bracing means for supporting the pipe in its upright position and thereby lessening the probability of burning the surface of the table, desk or the like.

The invention consists in the details of construction and in the combination and arrangement of the several parts of my improved tobacco pipe whereby certain advantages are attained, as will be hereinafter more fully set forth.

In order that my invention may be better understood, I will now proceed to describe the same with reference to the accompanying drawings, wherein:

Figure 1 is a view in top plan illustrating a pipe embodying the invention;

Figure 2 is a view partly in section and partly in elevation of the device as shown in Figure 1;

Figure 3 is a view in bottom plan;

Figure 4 is an enlarged detail sectional view

2 taken substantially on the line 4—4 of Figure 3; and

Figure 5 is an enlarged detail sectional view taken substantially on the line 5—5 of Figure 3. The tobacco pipe as herein embodied comprises a bowl 10 open at its top and bottom ends. A cup-shaped downwardly tapering member 11 is adapted to be inserted into the bowl 10 and the diameter of the upper edge of said member is such that the said edge engages the inside surface of the bowl 10 frictionally as at 12 so that the cup-shaped member 11 is retained in the bowl 10. The cup-shaped member 11 has a downwardly extending nipple-like bottom portion 13 and is arranged in the bowl 10 so that the lower end of the bottom portion 13 is located at a higher level than the lower edge surface 14 of the bowl 10. The tube 15 extends through a hole 16 in the wall of the bowl 10 and through the holes 17 and 18 arranged diametrically to each other in the wall of the bottom portion 13 of the cup-shaped member 11. The tube 15 and the nipple 13 of the cup-shaped member 11 are secured to each other by means of soldering in the form of a plug as at 19. This serves at the same time to close the clearance between the tube 15 and the rims of the holes 17 and 18. A hole 19a extending through the solder and a lateral opening 15a extending through the wall of the tube 15 connect the bore of the latter with the interior of the cup-shaped member 11. One end portion of the tube 15 is closed by a plug 20 embedded in the wall of the bowl 10 as shown. To facilitate setting the tube with the wall hole 15a thereof directed upwardly in the proper position in the bottom portion 13 of the cup member, the outer end of the tube may be provided with the slot 15b, in which to engage a screw driver or similar tool.

A pipe stem 21 is joined to the bowl 10 and has an axially extending bore 22 and a counterbore 23. The portion of the tube 15 projecting through the hole 16 fits snugly in the bore 22 so that the pipe stem 21 is reinforced by said tube in the end portion adjacent to the bowl 10. A pipe bit 24 has a reduced portion 25 fitting slidably into the counterbore 23. It is however, to be understood that the connection between the pipe stem 21 and the bit 24 may be made in any other suitable conventional manner. The bit is provided with a bore 26 communicating with the interior of the tube 15.

A plurality of ribs 27 are formed on and extend downwardly from the bit 24, and a pair of ribs 28 are formed on and extend downwardly

from the bottom edge surface 14 of the bowl 10. The ribs 27 are arranged diametrically opposite to each other and at right angles to the pipe stem 21. The lower faces of all of these ribs are arranged substantially in the same plane.

From the foregoing description it is thought to be obvious that a tobacco pipe constructed in accordance with the present invention will be kept cool on account of the recess formed in the bowl underneath the cup-shaped member and that such pipe is adapted to be placed safely in upright position on a table or the like.

I claim:

In a tobacco pipe, a bowl having a bore of a uniform diameter extending through the same and open at its two ends, a stem portion extending laterally from adjacent the lower end of said bowl and having a bore therethrough, a cup shaped receptacle positioned within the lower portion of the bore of said bowl, aligned holes in the lower portion of the receptacle and in line with said stem bore, a plug within the lower portion of said receptacle, a bore extending diametrically through the plug and in line with said holes in the lower portion of said receptacle and with the bore of said stem portion, said plug having a longitudinal hole opening into the diametrical bore and into said receptacle, a mouth-piece at the outer end of said stem portion, a metal tube projecting from the bore in

said stem portion into said bowl and through said aligned holes of said receptacle and said diametrical bore of said plug, said tube also having a lateral opening disposed in line with the said longitudinal hole of said plug, and a plug closing the projected end of said tube, the wall of the bowl having a recess in which the last mentioned plug is engaged.

CHESTER C. DOTY.
